UNITED STATES PATENT OFFICE.

CHARLES F. HILL, OF MIDDLE BRANCH, OHIO.

COMBINATION-LOCK.

SPECIFICATION forming part of Letters Patent No. 605,787, dated June 14, 1898.

Application filed March 13, 1897. Serial No. 627,294. (No model.)

To all whom it may concern:

Be it known that I, CHARLES F. HILL, a citizen of the United States, residing at Middle Branch, in the county of Stark and State of Ohio, have invented certain new and useful Improvements in Combination-Knob Doors; and I do hereby declare the following to be a full, clear, and exact description of the invention, such as will enable others skilled in the art to which it appertains to make and use the same.

The present invention has relation to door-knob locks; and it consists in the different parts and combination of parts hereinafter described, and particularly pointed out in the claims.

To the above end the invention consists in certain novel features and details of construction, as hereinafter fully described, illustrated in the drawings, and incorporated in the claims hereto appended.

In the accompanying drawings, Figure 1 is a sectional view through a pair of door-knobs and their attachments, showing the same applied to a door, the door-lock being omitted to avoid confusion. Fig. 2 is an enlarged detail section through the inside knob, showing the arrangement of the nested tumblers or disks. Fig. 3 is a perspective view of the inner knob with the cap removed to show the internal mechanism. Fig. 4 is a view in elevation of the same parts. Fig. 5 is a detail perspective view of the latch for holding the operative parts of the inner knob in locked relation. Fig. 6 is a section taken about centrally and transversely of the knob-spindle, looking toward the inner surface of one of the escutcheon-plates. Fig. 7 is a similar view looking toward the other escutcheon-plate.

Similar numerals of reference designate corresponding parts in the several figures of the drawings.

The improved knobs and the locking mechanism therefor are adapted to be used in connection with any ordinary mortise-lock. The outer knob 1 and the inner knob 2 are both hollow and of substantially cylindrical shape, as shown in Fig. 1. In the outer knob 1 is a lever 3, pivoted at one end, as shown at 4, and extending diametrically within the knob, said lever being provided at its opposite end with a pivoted plunger 5, which passes through

an opening in the inner side of the knob, where it is provided with a push button or head 6, whereby the plunger may be pushed inward for vibrating the lever 3 for a purpose hereinafter described. Arranged in the inside knob 2 is another lever 7, which is pivoted at one end, as shown at 8, and which extends diametrically within the knob, the free end of said lever being provided with an offset 8' on its inner edge for engaging the notches in the tumblers hereinafter described. The free end of the lever 7 is guided by a slotted bracket 9, the slot in which limits the vibratory movements of said lever, and both the levers 3 and 7 are connected at medial points by means of a wire or rod 10, the said rod extending through the hollow knob-spindle and serving, when the lever 3 is vibrated, to simultaneously and correspondingly vibrate the lever 7.

The inside knob has connected rigidly thereto a hollow spindle-section 11, which extends into the lock-case, where it is provided with a squared outer surface similar to other spindles for the purpose of engaging operatively the lock mechanism of the door. The outer knob 1 also has rigidly connected thereto a spindle-section 12, which passes into the section 11 and through said section into the inner knob 2. The spindle-section 12 may either be tubular or it may be solid and provided with a longitudinal groove to receive the wire or rod 10 and permit the longitudinal movement of the latter. Upon the inside of the outer escutcheon-plate is a spring 13, the free end of which bears against a polygonal collar 14, fast on the spindle-section of the outer knob, said spring serving to steady the movements of said knob, and most important of all to indicate to the person working the combination the proper distance to turn the outer knob for throwing the working parts of the knob into engagement for coupling the two knobs together and enabling the door to be opened. The opposite escutcheon-plate on the inside of the door also carries a spring 15 upon its inner side, the free end of said spring bearing against the spindle-section 11 for steadyng the movements thereof and compensating for any looseness where the improved knobs are applied to old locks and preventing the same

from turning too freely while working the combination. The lever 7 is actuated in an outward direction by means of a spring 16, which is preferably in the form of a piece of 5 spring-wire coiled, as shown at 17, around the fulcrum-pin of the lever 7, and having one terminal hooked to engage the inner edge of the lever 7 for forcing the same outward, while the opposite terminal of the spring is 10 hooked to engage the bracket or post 18, upon which the lever 7 is fulcrumed.

Mounted loosely in the inside knob is a series of disks or tumblers, three of such disks or tumblers being shown, although of course 15 the number may be increased or diminished at will without departing from the spirit of this invention. These disks are designated by the numerals 19, 20, and 21, the disk 19 being innermost and the disk 21 being outer side. Each of said disks is provided with an annular rim 22, indicating the outer rim, which is on the disk 19, 23 the intermediate rim, which is on the disk 20, and 24 the inner rim, which is on the disk 21. Each of the 20 disks is also provided with an inwardly-extending sleeve portion 25, and these sleeve portions are nested or telescoped one within the other and are all mounted to revolve freely within the hub portion 26 of the inside knob 2. Each of the rims 22, 23, and 24 is provided at a certain point with an open 25 slot or notch 27, and in working the combination it is necessary to bring all of the notches of the several rims into alinement, so that when the lever 7 is rocked inward at its 30 free end the offset 8' of said lever will enter said notches, thereby locking the several rims together and effecting a turning of the inside knob when the outer knob is turned. The disk 19 of the inner rim 24 is constantly locked to the spindle-section 12 by means of a collar 28, fast on said spindle-section, provided with a radial projection 29, which enters a notch 30 in the rim 24. Each of the rims is also provided 35 with either inwardly or outwardly extending projections 31, the said projections consisting of short screws which pass radially through said rims, so that the projection on one rim will engage the projection on the next adjacent rim, whereby when one rim is rotated it 40 is adapted to take up and rotate the adjacent rim. The inner rim need only have a projection on the outer surface and the outer rim need only have a projection on the inner surface, while the intermediate rim should have 45 projections on both its inner and outer surfaces. All of these projections are located in the same plane, so that upon the rotation of the rims said projections must necessarily 50 engage each other. These projections, which are in the form of screws, are also adjustable, and this is accomplished by providing each of the rims with a plurality of threaded perforations 32, so that its screw may be 55 removed and placed in any one of the perforations. This enables the combination to be changed at will.

33 designates a latch which is in the form of a transverse shaft or spindle 34, journaled in the inside wall of the knob and also in the bracket 9 above described. This shaft is provided exteriorly of the knob and upon the inner side thereof with a lever or handle 35, wherewith it may be turned, and said shaft is provided at a suitable point with a segmental projection 36, adapted to be rocked into the path of the lever 7 and so as to bear against the outer edge of said lever for the purpose of holding the lever inward in engagement with the notches 27 in the rims 22, 23, and 24. This permanently couples the two knobs together and enables them to be worked the same as ordinary knobs during the daytime. In the evening, or when it is desired to protect the house, the latch 33 is 80 thrown out of engagement with the lever 7, thus leaving the lever free to rock outward, thereby allowing the knobs to turn independently and the combination to be destroyed, thus preventing unauthorized persons from 85 entering the house, the house being accessible only to those who are acquainted with the combination.

By means of the construction above described the necessity of carrying a key for 95 operating a door-lock is entirely obviated. It is only necessary for a person acquainted with the combination to turn the outer knob a sufficient number of times to set all of the tumblers in motion. The knob is then stopped 100 at a predetermined point—for instance, with the button or head 6 uppermost. This brings the notch in the outer rim 22 in position to receive the offset 8' of the lever 7. The knob is then rotated in a reverse direction a predetermined distance, so as to bring the notch of the intermediate rim into alinement with the notch in the outer rim and also into position to receive the lever 7. The direction of the knob is now again reversed and the 105 knob is moved a certain distance, thereby bringing the notch in the inner rim 24 into alinement with the other notches, whereupon the plunger 5 may be pressed inward, thus rocking the lever 3 and consequently the lever 7 and bringing the offset into interlocked engagement with the notches 27. By now turning the other knob the inner knob will 110 be correspondingly turned, and by reason of the engagement of its spindle with the door-lock the lock will be operated and the door may be opened. The inside knob is provided 115 with a removable portion or cap 37, whereby access may be had to the mechanism contained in the inside knob for the purpose of changing the combination when desired.

It will be understood that the knobs and the locking mechanism therefor above described are susceptible of various changes in the form, proportion, and minor details of 120 construction, which may accordingly be resorted to without departing from the spirit or sacrificing any of the advantages of the invention.

Having now described the invention, what is claimed as new, and desired to be secured by Letters Patent, is—

1. A pair of hollow knobs each carrying a spindle-section, one of which is tubular, in combination with levers mounted in said knobs, a connection between said levers for simultaneously operating them, and locking mechanism arranged in one of the knobs and adapted to be engaged by one of said levers, substantially as and for the purpose specified.
2. Two hollow knobs, each having spindle-sections, one of which is tubular, in combination with levers arranged one in each knob, a connection between said levers for simultaneously operating them, means projecting exteriorly of one of the knobs for operating one of the levers, and locking mechanism in the other knob adapted to be engaged by the

lever therein, substantially as and for the purpose described.

3. The combination with a hollow door-knob, of a plurality of rotatable tumblers mounted therein and notched, a lever mounted in said knob for engagement with the notches in the tumblers, a spring for giving said lever a normal tendency, and an operating connection for said lever extending through the knob-spindle and adapted to be operated from the opposite knob, substantially as described.

In testimony whereof I have signed this specification in the presence of two subscribing witnesses.

CHARLES F. HILL.
